No. 879,106.

PATENTED FEB. 11, 1908.

J. KELLER.

PNEUMATIC HAMMER.

APPLICATION FILED DEC. 8, 1902.

UNITED STATES PATENT OFFICE.

JULIUS KELLER, OF PHILADELPHIA, PENNSYLVANIA, ASSIGNOR, BY MESNE ASSIGNMENTS, TO CHICAGO PNEUMATIC TOOL COMPANY, A CORPORATION OF NEW JERSEY.

PNEUMATIC HAMMER.

No. 879,106.

Specification of Letters Patent.

Patented Feb. 11, 1908.

Application filed December 8, 1902. Serial No. 134,272.

To all whom it may concern:

Be it known that I, JULIUS KELLER, a citizen of the United States, residing in the city and county of Philadelphia, State of Pennsylvania, have invented a new and useful Improvement in Pneumatic Hammers, of which the following is a specification.

In a contemporaneously pending application filed by me on December 11, 1900, bearing Serial No. 39,570, of which this application in its broad aspects is for certain purposes a division, I have shown among other features of my invention therein, a pneumatic riveter, comprising a cylinder having a piston 15 therein with a stroke greater than its own length, a valve mechanism at one end, only, of said cylinder and a grasping handle having a manually-operated throttle valve therein for controlling the initial admission of motive fluid to the tool.

I am aware that it has heretofore been proposed to construct a pneumatic tool having a cylinder provided with a piston, which has a stroke therein greater than its own length wherein the movements of said piston are controlled by a plurality of valve mechanisms, one, at each end of the cylinder. I have, however, found by practical experience, that such construction does not give good results in view of the severe usage to which tools of this character are put, particularly for riveting purposes, for the reason that the contact of the rivet set with the hot rivet tends to cause more or less heating, consequent expansion and contraction of the rivet set and nose piece of the tool, which is in turn imparted to the valve mechanism at the forward end of the cylinder, all of which is very objectionable, and I therefore found 40 that the best results are attained by the employment of a single valve mechanism located preferably in a valve box, contained between the grasping handle and the contiguous end of the tool cylinder, and to the 45 above ends my invention consists, broadly, in the combination of a cylinder and hammering piston therein, having a length of stroke greater than its own length, a tool holder in the forward end of the cylinder, adapted to 50 receive the shank of the button set, chisel or other working tool upon which said piston directly impacts, and a valve mechanism lo-

cated entirely at one end of said cylinder for controlling said piston, said valve mechanism being held preferably between the grasping handle and the contiguous end of said cylinder.

The invention further consists of other novel features of construction, all as will be hereinafter fully set forth and pointed out in the claims.

Figure 1 represents a longitudinal sectional view of a pneumatic tool, adapted for riveting and other purposes embodying my invention. Fig. 2 represents a longitudinal sectional view of a similar tool, omitting certain of the mechanism seen in Fig. 1. Fig. 3 represents a perspective view of the valve employed in detached position. Figs. 4 and 5 represent on an enlarged scale, sectional views of the stop valve mechanism employed in Fig. 1, the same being dispensed with in Figs. 2 and 3. Fig. 6 represents a longitudinal sectional view similar to Fig. 2 but showing the piston and valve in different positions.

Similar numerals of reference indicate corresponding parts in the figures.

Referring to the drawings: 1 designates the cylinder of a pneumatic riveter or other tool, having therein the hammering or reciprocating piston 2, which may be a plain cylindrical bolt having the striker 3 thereon or if desired the striker may be omitted, and a piston constructed as seen at 4 in the cylinder 5, may be employed, wherein the striker is dispensed with. As shown in my pending application aforesaid the piston 2 or 4 herein, as the case may be, has a length of stroke greater than its own length, and the valve mechanism is located wholly at one end of the cylinder, preferably in a suitable valve box 6, which is held in position between the extension 7 of the grasping handle 8, and the end of the contiguous cylinder. The compressed air enters the duct 9 outside of the grasping portion of the handle and passes through the port 10 into the passage 12 of the valve and in the construction seen in Fig. 1, it will be understood that the valve 13, has been moved to its extreme right-hand position, by the constant pressure upon the small area 14 thereof, thereby opening the ports 15 and thus permitting compressed air

to act upon the area 16 of the piston and force the latter into its extreme left-hand position as seen in Fig. 1, Fig. 2 representing the position of the piston just prior to its beginning the movement to the left towards the shank 23 of the working tool 24, upon which the blow is directly struck. It will be apparent, that the flow of the motive fluid into the passage 9, is controlled by means of the throttle valve 17, which is held normally in the position seen in Fig. 1, by the spring 18, said throttle valve being actuated by the lever 19, which is provided with the thumb piece 20 adapted to underlie the workman's thumb or finger, during the act of grasping the tool handle. The construction of the valve 13 will be clearly understood from Fig. 3, wherefrom it will be seen that the same consists of the hollow shell having the reduced neck 21 and the large differential area 22.

When the piston 2 reaches the position seen in Fig. 1, the port 25 is uncovered and live air enters it and passes into the passages 26 and 27 through port 28 upon the large differential area of the valve 13 and forces the same to its extreme left hand position, as seen in Fig. 6. The port 29 is now open to live air which passes through passage 30 and port 31 to the forward end of the cylinder and forces the piston back from the position seen in Fig. 1 into the position seen in Fig. 2. The piston in its rearward movement uncovers the port 32 and passages 26, whereby the air which held the valve 13 in its extreme left hand position seen in Fig. 6 will be free to escape through port 28, passage 26 and port 32 into the atmosphere through exhaust ports 33. The valve 13 can now move into the position seen in Figs. 1 and 2 by reason of the constant pressure on the small area 14. The ports 15 are now open to live air and the piston is forced from the position seen in Fig. 2 to the position seen in Fig. 1.

The port 29 which admits live air to the passage 30 and the port 31, is opened and closed at the proper intervals by the extension 34 on the valve 13, substantially in the manner described in my prior patents, as No. 647415, granted April 10, 1900. It will be understood that when the valve 13 is in the position seen in Fig. 6 and the piston moves from the position seen in Fig. 6 to the position seen in Fig. 2, the exhaust from the rear or right hand end of the piston to the atmosphere takes place through the ports 15, around the neck 21 of the valve 13, and thence through the ports 35 and 36 to the atmosphere. When the piston moves from the position seen in Fig. 2 to the position seen in Figs. 1 and 6, the exhaust from the forward or left hand end of the piston takes place, through the port 31, passage 30 and port 37 to the exhaust ports 35 and 36 hereinbefore referred to. It will be understood

that during the exhausting operation last described the valve 13 is in the position seen in Figs. 1, 2 and 5.

In the construction seen in Figs. 1, 4 and 5, I have shown my invention as employed with a stop valve consisting of heads 38 and 39, joined by the neck 40, said valve being held in the position seen in Fig. 5, by live air pressure entering through the port 41, and being moved in the opposite direction by the rod 42, which is moved backwardly by the pressure against its forward end by the ring 43, the rear end of said rod contacting with the stem 44 of said stop valve. I have deemed it unnecessary to show and describe in detail the precise operation of the stop valve and its ports and passage as the same are fully described in my pending application of which this is a division, and I make no claims herein to the stop valve or its adjuncts *per se*. In Figs. 2 and 6 I have shown the same construction of piston, distribution valve and tool cylinder as already described, since the piston 4 having no striker, has the same function, and is reciprocated in the same manner as the piston 2 provided with the striker 3.

While the construction seen in Figs. 1, 4 and 5, divided from my prior application referred to, discloses broadly the combination of a tool cylinder, having a hammering piston therein, having a length of stroke greater than its own length, a tool holder in the forward end of the cylinder adapted to receive the shank of the tool upon which the piston directly impacts, and a valve mechanism located entirely at one end only of the cylinder for controlling said piston, with a grasping handle for holding said valve mechanism in position, and has been found to give excellent results in practice, I have found it desirable in some instances to dispense with the stop valve mechanism altogether, and to employ merely the construction seen in Figs. 2, 3 and 6 herein, which I have fully described in detail. By the combination of the valve mechanism located at one end of the cylinder only and the grasping handle located substantially as shown, I am enabled to utilize the handle to hold the valve mechanism in position and to thereby render the same very accessible for the purpose of inspection and repairs.

By the employment of a cylinder and a piston therein having a stroke exceeding its own length, I am enabled to strike a very powerful and heavy blow directly upon the shank of the button set chisel or other working tool, and by constructing the piston of a plain cylindrical shape without any groove or ports therein, the same is rendered exceedingly durable and can be cheaply manufactured.

It will be understood by those skilled in the art that the employment of a solid, un-

grooved piston, in lieu of a piston having an annular groove intermediate its ends, when used in connection with a valve mechanism, located wholly at one end of the cylinder, 5 involves something more than the mere substitution of one piston for another, since it necessitates a total re-arrangement and positioning of the inlet and exhaust ports in the engine cylinder, particularly where a 10 valve mechanism of the general character described is employed, the differential valve of which is moved in one direction by fluid pressure upon the small differential area and in the opposite direction by intermittent 15 pressure, upon the large area of the valve, the latter having live air pressure constantly acting upon its interior. So far as I am aware, I am the first in the art to employ broadly a valve mechanism of this general 20 character in conjunction with a piston of the character described and my claims to these features are therefore to be interpreted with corresponding scope.

By the co-action between the parts comprising the tool proper, such as the cylinder, piston therein having a stroke greater than its own length, the valve mechanism located wholly at one end of the cylinder and held in position by the grasping handle, and the 30 grasping handle provided with a supply duct extending through it and having a manually-operated throttle valve controlling the admission of motive fluid to the tool is apparent, since I am enabled to produce a tool of great simplicity and durability at a minimum cost.

It will be understood that while the present invention is applicable for riveting and other work in metal as chipping, calking 40 and the like, I do not desire to be limited thereto, since my invention is applicable to all uses wherein a mallet and chisel have ordinarily been employed.

It will be apparent that I have omitted 45 from some of the views certain ports and passages for the sake of clearness of illustration, which are however shown in other views and it will be understood that I reserve to myself the right to make all such 50 changes as may come within the scope of my invention, and I do not therefore desire to be limited in every instance to the exact construction I have herein shown and described.

Having thus described my invention, what 55 I claim as new, and desire to secure by Letters Patent, is:—

1. In a pneumatic tool, a cylinder, a piston and a single valve controlling admission of 60 fluid to both ends of said piston, having a port for the fluid control of said valve opening into the cylinder at a greater distance from either end of the cylinder than the length of the piston.

2. In a pneumatic tool, a cylinder, a pis-

ton, a valve controlling admission of fluid to both ends of said cylinder and means for moving said valve operated through a port in the cylinder farther from either end of said cylinder than the length of the piston. 70

3. A pneumatic tool comprising a cylinder, a single valve located wholly at one end of said cylinder and controlling fluid admission to both ends of said cylinder, the latter having a port for fluid control of movement of 75 said valve and a hammering piston in said cylinder completely passing said port in each direction of its travel.

4. A pneumatic tool comprising a cylinder, a hammering piston therein having a stroke 80 in excess of its length, and a single valve for admitting fluid to both ends of said cylinder and itself controlled by fluid from the cylinder through a single port therein, and said piston passing beyond and uncovering said 85 port when in each of its extreme positions.

5. In a pneumatic tool, a cylinder, a hammering piston whose largest diameter and major portion comprises one unbroken surface, and suitable valve mechanism 90 located wholly at one end of said cylinder and exterior thereto for controlling the inlet of the motive fluid to opposite ends of the piston chamber to reciprocate the piston.

6. A pneumatic tool, comprising a cyl- 95 inder, a hammering piston located therein and having a length of stroke greater than its own length and a valve mechanism located wholly at one end of the cylinder, and controlling the reciprocations of the piston 100 in said cylinder, the latter having exhaust passages to the atmosphere uncontrolled by said valve mechanism.

7. A pneumatic tool, comprising a cyl- 105 inder, a hammering piston located therein, and having a length of stroke greater than its own length and a valve mechanism located wholly at one end of the cylinder and exterior thereof, and controlling the reciprocations of the piston in said cylinder, the 110 latter having exhaust passages to the atmosphere uncontrolled by a valve.

8. A pneumatic tool, comprising a cyl- 115 inder, a hammering piston located therein and having a length of stroke greater than its own length, and a valve mechanism located wholly exterior to the body of the cylinder in alignment therewith and operated by fluid pressure alone and controlling the reciprocations of the piston in said cylinder, the 120 latter having exhaust passages to the atmosphere uncontrolled by said valve mechanism.

9. In a pneumatic tool, a cylinder, a hammering piston therein having a length of stroke greater than its own length and comprising a plain, solid, ungrooved cylindrical bolt and a valve mechanism operated by fluid pressure alone and located wholly at one end of said cylinder, the latter having free exhaust ports leading to the atmosphere 130

- and covered by said piston when in its forward position, said exhaust ports being uncontrolled by said valve mechanism.
10. In a pneumatic tool, the combination 5 of a cylinder, a hammering piston therein and having a length of stroke greater than its own length, a valve block in axial alignment with and abutting against one end of the cylinder, a motive fluid controlling valve 10 in said valve-block and in axial alignment with said piston and a socket inclosing the valve block and engaging the end of the cylinder to draw the latter and the valve block together.
15. 11. In a pneumatic tool, a cylinder, a hammering piston consisting of a plain cylindrical bolt of uniform diameter throughout its major portion, and suitable valve mechanism located wholly at one end of said 20 cylinder exterior thereto for controlling the inlet of the motive fluid to the opposite ends of the piston chamber to reciprocate the piston, in combination with a grasping handle secured to the end of said cylinder contiguous to said valve mechanism.
25. 12. In a pneumatic tool, a cylinder, a hammering piston consisting of a plain cylindrical bolt of uniform diameter throughout its length, a suitable valve mechanism located wholly at one end of said cylinder and exterior thereto for controlling the inlet and exhaust of the motive fluid to opposite ends of the piston chamber to reciprocate the piston, a grasping handle having an inlet 30 passage for the motive fluid and a manually-operated throttle valve for controlling the initial admission of motive fluid to the tool.
35. 13. In a pneumatic tool, the combination 40 of a cylinder, a hammering piston therein, comprising an ungrooved, cylindrical bolt and having a length of stroke greater than its own length, a tool holder in the forward end of the cylinder, adapted to receive the 45 shank of a tool, upon which said piston directly impacts, a valve mechanism containing a valve operated by fluid pressure alone and located entirely at one end of said cylinder for controlling said piston, and 50 means, for retaining said valve mechanism in assembled position with respect to said cylinder.
55. 14. In a pneumatic hammer, the combination 55 of a cylinder, a hammering piston therein comprising an ungrooved, cylindrical bolt and having a length of stroke greater than its own length, a tool holder in the forward end of the cylinder and adapted to receive the shank of a tool, upon which said 60 piston directly impacts, a grasping handle secured to the rear end of said cylinder, and a valve mechanism located entirely at one end of said cylinder for controlling said piston, said mechanism being contained between 65 said handle and cylinder and comprising a valve driven by fluid pressure alone, said fluid pressure acting constantly on one area of said valve and intermittently on its other area.
15. In a pneumatic tool, the combination 70 of a cylinder, a hammering piston therein comprising an ungrooved, cylindrical bolt and having a length of stroke greater than its own length, a tool holder in the forward end of the cylinder and adapted to receive the shank of a tool upon which said piston directly impacts, a grasping handle secured to the rear end of said cylinder and a valve mechanism located entirely at one end of said cylinder for controlling said piston, said 80 valve mechanism being held between said handle and the contiguous end of said cylinder.
16. In a pneumatic tool, the combination 85 of a cylinder, a hammering piston therein comprising an ungrooved, cylindrical bolt and having a length of stroke greater than its own length, a tool holder in the forward end of the cylinder adapted to receive the shank of a tool, upon which said piston directly impacts, a grasping handle secured to the rear end of said cylinder, a valve box located between said handle and the end of said cylinder, and a valve in said box for controlling said piston, said valve being 90 operated by fluid pressure alone and the forward end of said cylinder being provided with free exhaust ports to the atmosphere uncontrolled by said valve.
17. In a pneumatic tool, the combination 100 of a cylinder, a hammering piston therein comprising an ungrooved, cylindrical bolt and having a length of stroke greater than its own length, a tool holder in the forward end of the cylinder adapted to receive the 105 shank of a tool, upon which said piston directly impacts, a grasping handle secured to the rear end of the said cylinder, a valve mechanism located wholly at one end of said cylinder and held between said handle and the rear end of said cylinder and comprising a hollow differential valve actuated in one direction by constant pressure and in the opposite direction by live air pressure, said cylinder having free exhaust ports in its forward portion uncontrolled by any valve, a pressure supply duct extending through said handle, for the purpose of conducting compressed air to said valve mechanism, and a manually-operated throttle valve in said 115 handle for controlling the initial supply of motive fluid to the tool.
18. In a pneumatic tool, the combination 120 of a cylinder, a hammering piston therein comprising an ungrooved, cylindrical bolt and having a length of stroke greater than its own length, a tool holder in the forward end of the cylinder adapted to receive the shank of a tool, upon which said piston directly impacts, a grasping handle secured to 130

- the rear end of said cylinder, a valve mechanism located wholly at one end of said cylinder and held between said handle and the rear end of said cylinder, a pressure supply duct extending through said handle outside of the grasping portion thereof, for the purpose of conducting compressed air to said valve mechanism, and a manually-operated throttle valve in said handle for controlling 10 the initial supply of motive fluid to the tool.
19. In a pneumatic tool, the combination of a cylinder, a hammering piston therein, having a length of stroke greater than its own length, said piston being a plain, cylindrical bolt having an unbroken exterior periphery throughout its greatest diameter, a tool holder in the forward end of the cylinder adapted to receive the shank of a tool upon which said piston directly impacts, a grasping 20 handle secured to the rear end of said cylinder, and a valve mechanism located entirely at one end of said cylinder and retained between said handle and the contiguous end of said cylinder for controlling 25 said piston, said mechanism comprising a hollow differential valve, and said cylinder containing a series of free exhaust ports leading to the atmosphere and uncontrolled by said valve.
20. In a pneumatic tool, the combination of a cylinder, a hammering piston therein having a length of stroke greater than its own length, said piston having an unbroken exterior periphery throughout its greatest 30 diameter, a tool holder in the forward end of the cylinder, means for retaining said tool holder in position within said cylinder, said tool holder being adapted to receive the shank of a tool upon which said piston directly impacts, a grasping handle secured to the rear end of said cylinder, and a valve mechanism located entirely at one end of said cylinder for controlling said piston, said mechanism comprising a hollow differential 35 valve, and said cylinder containing a series of free exhaust ports, leading to the atmosphere and uncontrolled by said valve.
21. In a pneumatic tool, the combination of a cylinder, a hammering piston therein, having a length of stroke greater than its own length, said piston having an unbroken exterior periphery throughout its greatest diameter, a tool holder in the forward end of the cylinder, means for retaining said tool holder in position upon said cylinder, said tool holder being adapted to receive the shank of a tool upon which said piston directly impacts, a grasping handle secured to the rear end of said cylinder, and a valve mechanism containing a differential valve 50 located entirely at one end of said cylinder for controlling said piston, said cylinder hav-
- ing free exhaust ports to the atmosphere uncontrolled by said valve.
22. In a pneumatic tool, the combination 65 of a cylinder, a hammering piston therein, having a length of stroke greater than its own length, said piston having an unbroken exterior periphery throughout its greatest diameter, a tool holder in the forward end of the cylinder, means for retaining said tool holder in position upon said cylinder, said tool holder being adapted to receive the shank of a tool upon which said piston directly impacts, a grasping handle secured to 70 the rear end of said cylinder and a valve mechanism containing a hollow differential valve located entirely at one end of said cylinder for controlling said piston, said cylinder having free exhaust ports to the atmosphere 75 uncontrolled by said valve.
23. In a pneumatic tool, a cylinder, a hammering piston therein, having a length of stroke greater than its own length and comprising an ungrooved, cylindrical bolt 80 having an unbroken periphery throughout its length, a tool holder in the forward end of the cylinder and adapted to receive the shank of a tool upon which said piston directly impacts, and a valve mechanism located wholly at one end of said cylinder for controlling said piston, said mechanism consisting of a hollow differential valve, in alignment with said piston and moving in the same direction as the latter and having air 85 pressure constantly within its interior.
24. In a pneumatic tool, a cylinder, a hammering piston therein having a length of stroke greater than its own length and comprising an ungrooved, cylindrical bolt having an unbroken periphery throughout its length, a tool holder in the forward end of the cylinder and adapted to receive the shank of a tool, upon which said piston directly impacts and a valve mechanism located wholly at one end of said cylinder for controlling said piston, said mechanism consisting of a hollow differential valve, in alignment with said piston and moving in the same direction as the latter and having air 90 pressure constantly within its interior.
25. In a pneumatic tool, a cylinder, a hammering piston therein having a length of stroke greater than its own length and comprising an ungrooved, cylindrical bolt having an unbroken periphery throughout its length, a tool holder in the forward end of the cylinder and adapted to receive the shank of a tool, upon which said piston directly impacts and a valve mechanism located wholly at one end of said cylinder for controlling said piston, said mechanism consisting of a hollow differential valve, in alignment with said piston and moving in the same direction as the latter and having air 95 pressure constantly within its interior.
26. In a pneumatic tool, a cylinder, a hammering piston therein having a length of stroke greater than its own length and comprising an ungrooved, cylindrical bolt having an unbroken periphery throughout its length, a tool holder in the forward end of the cylinder and adapted to receive the shank of a tool, upon which said piston directly impacts and a valve mechanism located wholly at one end of said cylinder for controlling said piston, said mechanism consisting of a hollow differential valve, in alignment with said piston and moving in the same direction as the latter and having air 100 pressure constantly within its interior, ports 25, 26, 27 and 28 for admitting live air pressure to the larger area of said valve, ports 32 and 33 in the forward end of said cylinder and coacting with said ports 25, 26, 27 and 105 28 for permitting exhaust from said larger area, ports 29, 30 and 31 for admitting live air to the forward end of said piston and ports 37, 35 and 36 for permitting exhaust from the forward end of said piston.
